TAG CONVERTER

George H. Kress, Johnson City, and Myron F. Davis, Jr.,
Binghamton, N. Y., assignors to International Business Machines Corporation, New York, N. Y., a corporation of New York

Application December 31, 1954, Serial No. 33,770

Term of patent 14 years

(Cl. D64—11)

The figure is a perspective view of a tag converter, embodying our design.

The right side and rear of the converter are substantially plain.

We claim:

The ornamental design for a tag converter, as shown and described.
